SOLOMON A. WOODS, OF BOSTON, MASSACHUSETTS.

CIRCULAR SAWING MACHINE.

SPECIFICATION forming part of Letters Patent No. 364,328, dated June 7, 1887.

Application filed January 4, 1886. Serial No. 187,593. (No model.)

To all whom it may concern:

Be it known that I, SOLOMON A. WOODS, of Boston, in the county of Suffolk and State of Massachusetts, have invented a certain new and useful Improvement in Circular Sawing Machines, of which the following is a specification.

My invention relates to circular sawing machines; and it consists in certain improvements in the construction and arrangement of the several parts of the same, substantially as hereinafter described and claimed.

In the drawings, Figure 1 is a side elevation of a saw-bench provided with my improvements. Fig. 2 is a top plan view of the same. Fig. 3 is an enlarged view of Fig. 2, showing the details of the working parts. Fig. 4 is an enlarged face view of a portion of the frame and mechanism from the opposite side shown in Fig. 1. Fig. 5 is a side view of Fig. 4, partly in section, to show the connection of some of the working parts. Fig. 6 is a detail view of a portion of Fig. 5, having a different adjustment of the parts. Fig. 7 is 25 the same as Fig. 6, with the parts swung into another adjustment. Fig. 8 is a reduced view of the same parts as shown in Fig. 6, with the other parts belonging thereto shown in connection with the same. Fig. 9 is a view of a 30 portion of Fig. 2, with the parts shown as adjusted differently.

A is the frame of the saw-bench. T is the top of the bench. S is the circular saw, mounted upon a shaft in bearings in the frame 35 in the usual manner, and driven by a belt from pulley P on shaft p.

On one side of the frame, and near one corner of it, are attached two brackets, a a', projecting outward, in which is journaled the upper shaft s in such manner as to be capable 40 of sliding longitudinally as well as revolving therein. The part of shaft s which passes through the upper bearing, a, is of larger diameter than the part passing through the lower bearing, a', there being a square shoulder between these two parts near the middle of the shaft. Just beneath this shoulder, and fitting the smaller part of the shaft, so as to allow the latter to turn therein, is applied the 45 box a². This box on one side carries the ear

a³, and on the other the journal-bearing s² of the horizontal shaft s', which is made in the form of a long sleeve. The shaft s' has attached to one end the pulley p', and on the other the speed or cone pulley p², and the sleeve-bearing s² abuts at each end against these pulleys, which prevents endwise movement of the shaft in the bearing. Through ear a³ is made a vertical hole with a screw-thread, and fitted to this is the screw a⁴, depending from a part of the bracket a, to which it is attached by a vertical journal-bearing, and a collar, e, on its upper end, above the latter. The screw a⁴, therefore, supports box a², shaft s, and shaft s', with the pulleys attached to the latter, and raises or lowers all of them together. An arm, a', projecting from the bracket a, supports the horizontal sleeve-bearing a⁶, carrying the shaft s¹³, which has on its outer end the hand-wheel W and on its inner end the bevel-gear c', meshing into bevel-gear c², attached to screw a⁴. By turning the hand-wheel, therefore, box a² is raised and lowered.

An arm, a', extends around from the rear of the frame outside the path of the shaft s' in rising and falling, and supports on its outer end the collar c³, which fits the shaft closely, and serves to limit the path of the box a² in its downward movement. Collar c³ is also provided with a set-screw in one side, by means of which the shaft s may be prevented from turning around when the screw is set up.

The pulley p² belts onto a pulley, p³, on shaft p, as shown, the slight alteration in the tension 85 of the belt by the raising and lowering of the former not being material. Shaft s has fixed on its upper end a collar, s³, provided with ears s⁴ s⁴, projecting upward on each side, and holes through said ears in a direction horizontal and tangential to shaft s, as shown. On the upper end of collar s³ is attached a head, E, carrying the arm E'. This attachment is effected by having ears e on the lower end of the head, which fit between the ears s⁴, and 90 are provided with holes registering with the holes in the latter. Bolts s⁵, Figs. 5 and 7, are passed through the ears s⁴ e, securing them together. By removing one of these bolts on one side of collar s³ the one on the opposite 95

side serves as a pivot upon which the head E can be tilted up, as shown in Fig. 6, and the arm E' be swung out of the way of the table; or both bolts can be removed and head E be taken off of shaft s and replaced very readily.

In order to hold the head E in the inclined position shown in Fig. 6, its lower surface, which comes over the longitudinal center of shaft s, is provided with a downwardly-projecting ear, 10 to e', which has pivoted on its lower end the sliding bolt e'', which moves up and down in an axial hole formed in shaft s downward from its upper end, and a set-screw through the side of the shaft and collar s' enters this hole transversely, and, being screwed up against sliding bolt e'', secures it in any desired position, and the head E attached thereto.

Head E carries the pulley p⁴, mounted on the horizontal shaft or stud p⁵, in line with 20 pulley p', from which it is belted when head E is in place upon collar s'. A pinion, e⁸, is attached to pulley p⁴ and turns on shaft p⁵. On the head E is attached another horizontal stud, p⁶, on which revolves the gear-wheel e⁷, 25 to which is attached the pinion e⁹, revolving with it. These pinions are covered by a housing covering them, so that the workman cannot be injured by them. The arm E' has upon it two short arms, e¹⁰ e¹¹, Figs. 2, 3, and 8, to 30 which are pivoted the arms e¹² e¹³ at one end, the latter carrying the long sleeve e¹⁴, attached to their opposite ends. Mounted axially in this sleeve is the revolving shaft p¹, parallel with arm E'. This shaft carries on one end 35 the gear-wheel e¹⁵, engaging with pinion e⁹, and on the other the toothed feed-wheel F in line with the saw S, which engages with the surface of the board and feeds it along over the table.

40 The gear-wheel e¹⁵ of the shaft of the feed-wheel F is driven by the power communicated through the pinion e⁹ with the latter placed on the front side of the former—that is, on the side of the shaft p¹ of the feed-wheel from 45 which the board is fed in under it, commonly called the "feed-in" side. The effect of this arrangement when the feed-wheel is being driven is that the direction of rotation of the pinion e⁹ necessarily draws downward upon 50 the gear-wheel e¹⁵ and its shaft and the feed-wheel F, and presses the latter upon the surface of the board being fed through the machine. I am therefore enabled to dispense with weighted arms or levers attached to sleeve 55 e¹⁴ to press the feed-wheel upon the board. Furthermore, when a larger and heavier board is fed through under the feed-wheel F, requiring more power to be transmitted through the pinion-wheel e⁹, to drive the board through, 60 this pinion-wheel presses down harder upon its gear-wheel e¹⁵ and thus automatically increases the pressure upon feed-wheel F in proportion to the greater amount of work it is required to do. This feature of the construction is especially valuable where light and 65 heavy boards are indiscriminately fed through

the machine, because it regulates the bearing and friction of the feed-wheel F upon the board so as to not have too much friction and consequent loss of power with light boards on the one hand, or too little pressure of the feed-wheel and failure of driving-power with heavy boards on the other.

70 It will be observed that the arms e¹² e¹³ are braced apart at their pivoted ends by the rod e¹⁶, and that their pivots are so arranged as to allow the gear-wheel e¹⁵ to remain engaged with pinion e⁹ as the arms and attached sleeve e¹⁴ turn to rise and fall on the pivots, thus allowing the feed-wheel F to move up and down to accommodate itself to different thicknesses of lumber while feeding them through the machine without disturbing the operation of its driving mechanism. To one of the arms e¹² a hand-wheel and screw, q, is attached by the 80 screw passing downward through a screw-threaded hole in the arm just above arm E'. By turning hand-wheel q the sleeve e¹⁴ may be adjusted at different heights from the saw-table.

90 The arm E' carries at its outer end the curved arm a¹, which is arched over sleeve e¹⁴, so as not to interfere with the rise and fall of the feed-wheel, and supports on its outer end the curved shield a², protecting the saw.

95 A post, O, Fig. 8, rises at one corner of the saw-table, and to its top is attached, by a universal pivot-joint, the rod o. This rod has its outer end screw-threaded and check or clamp nuts o' o' fitted thereto. On top of arm E' is fixed a stud, o², having a slot or groove cut in it from its top edge downward a sufficient distance to allow the rod o to be dropped therein. When this is done, the nuts o' o' are screwed up and the arm E' is securely 100 braced.

If it be desired to use the saw-bench without the feed attachment, it can either be swung into the position shown in Fig. 9 or tilted up, as shown in Fig. 8; or if it be desired to cut 110 off the ends of long boards, the head E can be disconnected from shaft s and removed with all the attached parts of the feed mechanism above the table. This adapts the saw-bench 115 feed to be used in corners of the room or against partitions or near other machines, and removed out of the way at pleasure by some one of these adjustments under almost any conceivable circumstances.

120 The saw-table is raised and lowered at one end by a crank and screw placed underneath it in the usual manner.

N is a gage or guide having a straight-edge next the saw, and moving toward or away from it in the groove n in the table-top. A lever, n', is pivoted upon a vertical pin to the table-top at one end, and at the other has the handle n² projecting beyond the top. Opposite to the guide N a short link, n³, is pivoted at one end to lever n' and at the other end to 130 the top of the guide. By moving the lever horizontally the guide will be adjusted to and

fro in groove n . To secure it in place, a stationary rack, n^4 , is attached to the saw-table, and the lever n' is provided with a downwardly-projecting metal edge, n^5 , fitted to enter the teeth of the rack. By lifting the lever slightly it is disengaged from the rack and moved along to the desired place, when by dropping it it re-engages with the rack and holds the gage n in position. By accurately laying off the rack-teeth and providing them with indicating numbers the gage may be adjusted at a predetermined distance from the saw without measuring to determine it when it is being adjusted.

15 By pivoting the lever n' at one end to the table and having its handle at the other end and attaching the guide N to its central part I am enabled to remove its pivot-fastening to the farther edge of the table, away from beneath arm E' and its attachments, and get a longer leverage than if the pivot were between the handle and the place where the gage was attached.

It is evident that other well-known forms 25 of detachable fastenings than those shown may be employed to secure the head E to the shaft s below the surface of the table-top, if preferred, without departing from the spirit of my invention. It is also evident that a single 30 pivoted arm, e^1 , may be employed to carry the bearing-sleeve e^8 of the feed-wheel F instead of two, if desired.

What I claim as new and of my invention is—

35 1. The combination of the table T , the feed-wheel F , the arm E' , projecting horizontally over the table and carrying the shaft of said feed-wheel, the vertical shaft s , carrying the arm and adapted to rise and fall vertically 40 and be revolved in its bearings, and mechanism adapted to elevate and lower said shaft, substantially as described.

2. The combination of the table T , the feed-wheel F , the arm E' , projecting horizontally 45 over the table and carrying the shaft of said feed-wheel, the vertical shaft s , carrying the arm, and adapted to rise and fall vertically and be revolved in its bearings, the sleeve a^3 , and the screw a^4 , journaled in the table-frame, 50 substantially as described.

3. The combination of the table T , the feed-wheel F , and the arm E' , projecting horizontally over the table, carrying the shaft of said feed-wheel, and pivoted upon a hinge, e^8 , at its 55 head part E , with the axis of the hinge horizontal and parallel to the face of said feed-wheel, whereby the said arm and wheel are adapted to be swung upward on the hinge in a plane transverse to that of said wheel, substantially as described.

4. The combination of table T , the feed-wheel F , and the arm E' , projecting horizontally over the table and carrying the bearings of said feed-wheel, and having the head part E 65 extending below the table surface and secured at its lower end to its support by a joint and

detachable fastenings, substantially as described.

5. The combination of the table T , the head E , and arm E' , projecting horizontally over the table and mounted upon pivots upon the latter, adapted to allow said arm to swing both horizontally and vertically thereon, the arm or arms e^1 , pivoted to said arm E' , and carrying the sleeve-bearing e^8 , the feed-wheel F , 75 mounted upon a shaft supported in said sleeve-bearing, and the train of gearing adapted to drive said shaft and mounted upon and supported by said head E and arm E' , substantially as described. 80

6. The combination of the table T , the head E , and arm E' , projecting horizontally over the table, mounted upon pivots upon the latter, adapted to allow said arm to swing both horizontally and vertically thereon, and carrying the train of gear-pinions $e^9 e^5$, with mechanism for driving the latter, the arm or arms e^1 , pivoted to arm E' and carrying the sleeve-bearing e^8 , the shaft p^7 , journaled in said sleeve-bearing and carrying the gear e^9 , and the feed-wheel F , mounted upon said shaft, substantially as described. 85

7. The combination, with the saw-table T and its frame, of the shaft s , head E , and horizontal arm E' , adjustable vertically together, 95 the shaft s' and its pulleys $p^1 p^2$, mounted in sleeve a^3 and adjustable with shaft s , the pulley p^4 , mounted on head E , the feed-wheel F and its shaft p^7 , mounted upon arm E' , and gear mechanism, substantially as set forth, connecting pulley p^4 with shaft p^7 , whereby all the parts are adjustable vertically together, as set forth, while shaft p^7 is being driven from pulley p^2 , substantially as described. 100

8. The combination of the table T , the horizontal arm E' , and its head E , secured by detachable fastenings in ears $s^4 e$, below the table-top, the pulley p^4 and feed-wheel shaft p^7 , connected by gear mechanism, substantially as set forth, and mounted upon said arm and head 110 above said fastenings, and the pulley p^1 , mounted on shaft s' , below said fastenings in position to drive pulley p^4 by a belt, substantially as described.

9. The combination of the table T , the saw 115 S , the gage or guide N , adapted to bear against one side of the lumber passing the saw, the head E , and arm E' , projecting horizontally over the table and mounted upon a pivot upon the latter, adapted to allow said arm to swing 120 horizontally thereon, the arm or arms e^1 , pivoted to said arm E' and carrying the sleeve-bearing e^8 , the feed-wheel F , mounted upon a shaft supported in said sleeve-bearing and adapted to be swung with arm E' , to give 125 greater or less bearing of the lumber fed by it against gage N , and the train of gearing adapted to drive said feed-wheel shaft, and mounted upon and supported by said head, substantially as described. 130

10. The combination of the table T , the saw S , the head and arm $E E'$, projecting horizon-

tally over the table, the arm or arms e^1 , pivoted to said arm E' and carrying the sleeve-bearing e^3 , the shaft p^1 , journaled in said sleeve-bearing and carrying upon it the feed-wheel 5 F and gear-wheel e^6 , the pinion e^5 , engaging with pinion e^9 , and mounted upon the front or feed-in side of the shaft of the latter, and the train of gearing adapted to drive said pinion e^5 , and mounted upon and supported by said head, substantially as described.
